3 Claims. (Cl. 179—171)

My invention relates to a coupling circuit for connecting a generator to a load.

When a plurality of electric circuits are fed from a common generator, the internal resistance of the latter brings about an undesirable mutual coupling of the circuits. This take place for instance, in carrier wave telephony-or-telegraphy, in which a plurality of carrier wave systems, each consisting of a certain number of channels, are operated simultaneously. It is desirable to feed the channels of the various systems operating at the same carrier wave frequency from a common carrier generator, but this introduces difficulties. More particularly, the internal resistance of the common generator involves cross-talk from the channel of one system to the corresponding channel of the other system which, of course, is undesirable.

The object of my invention is to overcome the above difficulties and for this purpose I connect the common generator to the loads through a degenerative back-coupled amplifier, and so adjust the degenerative back-coupling that the amplifier has a low internal resistance.

In order that the invention may be clearly understood and readily carried into effect, I shall describe the same in more detail with reference to the accompanying drawing in which the single figure is a schematic diagram of a circuit embodying the invention.

As shown in the drawing, a generator G having an internal impedance Z_i is connected to the input terminals 1 and 2 of an amplifier A having output terminals 3 and 4. Connecting to terminals 3 and 4 are two modulators M_1 and M_2 which form part of two different carrier wave systems and to which the carrier wave produced by the generator G is to be supplied.

Without interposition of amplifier A between the generator and modulators M_1 and M_2 , a coupling would be set up across the internal impedance Z_i between both carrier wave systems. The same would apply if an amplifier without degenerative backcoupling were used, because the internal resistance of the amplifying tube would act as a coupling impedance.

According to the invention amplifier A is back-coupled in a degenerative manner. As shown the amplifier comprises a thermionic tube 5 having a grid 9, a plate 10, and an incandescent cathode 11, supplied with heating current by a battery 16. Plate 10 is connected through a condenser 7 to one end of the primary winding 12 of a coupling transformer 8; the other end 55 of this winding being connected to the cathode

11. Connected between plate 10 and cathode 11 is a resistance 6 and a source of plate voltage 15. Connected across winding 12 is a potentiometer P having a variable tap 13 connected through terminal 2, generator G and terminal 1 to grid 9. 5

By means of a potentiometer P a portion β of the alternating voltage set up between cathode 11 and plate 10 is applied to the grid circuit, whereby the coupling between the two carrier wave systems will be materially reduced. 10

I have found that degenerative back-coupling involves variation of the internal resistance of the amplifying tube. For example, if tube 5 without back-coupling has an internal resistance R_i and an amplifying factor g , the internal resistance of the amplifying tube with degenerative back-coupling may be represented by the formula: 15

$$R_i' = \frac{R_i}{1 + \beta g} \quad (1) \quad 20$$

By giving β a high value, R_i' can be reduced to an arbitrarily small value, thus at the same time appreciably reducing the coupling between the electric circuits connected to the output circuit of the amplifier. For instance, if $R_i=5,000$ ohms, $g=25$, and $\beta=20$, then R_i' will be equal to 25 10 ohms.

The coupling between the load circuits is further decreased by inserting resistances R in the output circuit of the amplifier. Resistance R should have a large value relatively to resistance R_i . For example, if $R_i=10$ ohms, R should have a value of about 125 ohms.

While I have described my invention in connection with specific examples and applications, I do not wish to be limited thereto but desire the appended claims to be construed as broadly as permissible in view of the prior art.

What I claim is:

1. A circuit arrangement comprising a common source of voltage having an internal impedance, a plurality of electric circuits fed from said source, and means for reducing the coupling between said electric circuits comprising a degenerative back-coupled amplifier connected between said circuits and said source, the back-coupling being so adjusted that the amplifier has a low internal resistance. 40 45

2. A circuit arrangement comprising a common source of voltage having an internal impedance, a plurality of electric circuits fed by said source, and means for reducing the coupling between said electric circuits comprising a degenerative back-coupled amplifier connected be- 50 55

tween said circuits and source, and resistances connected between said amplifier and said electric circuits, the back-coupling being so adjusted that the amplifier has a low internal resistance.

5 3. A circuit arrangement comprising a generator having an internal impedance, a plurality of loads fed from said generator, and an amplifying circuit connecting said loads to said generator and comprising an amplifying tube having an 10 anode, a cathode and a grid, a plate circuit for

said tube insulating a coupling transformer having a primary winding and a secondary winding connected to said loads, a potentiometer connected across said primary winding, and a grid circuit for said tube including said generator and a portion of said potentiometer, said portions being so selected that the amplifying tube has a low internal resistance.

THOMAS SAMUEL SKILLMAN. 10
